UNITED STATES PATENT OFFICE.

SÁNDOR WEISZ, OF NEW YORK, N. Y.

SOFT FOLD-COLLAR.

1,319,499.

Specification of Letters Patent. Patented Oct. 21, 1919.

Application filed November 23, 1917. Serial No. 203,521.

To all whom it may concern:

Be it known that I, SÁNDOR WEISZ, a citizen of the United States, residing in the city of New York and the county of New York 5 and State of New York, have invented certain new and useful Improvements in Soft Fold-Collars, of which the following is a full, clear, and exact description, such as will enable others skilled in the art to which 10 it pertains to make, construct, and use the same, reference being had to the accompanying drawings, and to characters of reference marked thereon, forming a part of this specification.

15 The invention relates to improvements in soft collars of the well known turn down type.

The principal object of the invention is to provide the neck band of a soft fold-collar 20 with that degree of stability which is so essential in order to maintain the shape of the turned portion and to prevent it from wrinkling, by quilting the neck band thereof in such a manner as to dispense with even the 25 simplest form of the ordinary permanently contained, or removably secured stiffening devices, such as celluloid, featherbone, sheet metal or the like, which are common in the art and to which many objections have 30 been found.

The invention therefore consists in incorporating between the plies or thicknesses of the fabric of which the neck band is composed, a single strip or strips of some suitable soft substance or material, preferably of the same fabric at more or less frequent intervals, or throughout the entire length of the neck band, and thereafter sewing or quilting the same together in such a manner 40 as to impart to said neck band that desired degree of stability obtained thereby and which is necessary to maintain the collar in the proper extended, slightly and comfortable position.

45 Referring to the sheet of drawings, in which I have illustrated the preferred embodiment of my invention I will proceed to describe the same, having it understood that I am not limited to the specific details of construction shown and described, as it is manifest that these may be modified and changed without departing from the spirit and scope of the invention.

Figure 1 represents a plan view of a soft

fold-collar embodying my invention, the 55 collar being laid out flat.

Fig. 2 represents a similar view of a modified form of the neck band of a soft fold-collar, a portion of the band ply being broken away for convenience of illustration. 60

Fig. 3, represents on an enlarged scale a portion of the neck band embodying my invention; and

Fig. 4 represents a horizontal cross-section taken on line $x-x$ of Fig. 3. 65

Similar characters of reference refer to like parts throughout the specification and drawings.

In the drawings, 1 represents the top and 2 represents the neck band of a soft fold-collar of ordinary design secured together in the usual and well known manner. The neck band 2 is composed, preferably of two plies or thicknesses of suitable material which are sewed together along the front, 70 lower and end edges and being provided with the usual button holes so that the collar can be readily fastened in position on the neck band of the shirt.

In order to provide an efficient, durable 80 and inexpensive neck band which shall meet all of the above enumerated requirements without the use of the hitherto employed, permanently contained, or removably secured stiffening devices, such as celluloid, 85 featherbone, sheet metal or the like, I incorporate between the plies or thicknesses of the fabric, of which said neck band is composed, a single strip or a plurality of strips, lettered respectively 5, 6 and 7, of any 90 suitable soft material which may be, preferably of the same fabric as the plies of which the neck band is composed and sewing or quilting the same together by means of stitching 8, inserted through the band plies 9 95 and 10 and the strips of soft material, or similar fabric 5, 6, and 7, as clearly indicated in the drawings.

From an inspection of Fig. 1 of the drawing it will be noticed, that I have incorporated between the two plies of the neck band, at more or less frequent intervals, a plurality of strips of fabric by sewing or quilting the strips together with the plies of the neck band, thereby imparting to said neck band that stability which is so much desired and which prevents the collar from wrinkling, and as a consequence keeps its 100 105

shape as long as the collar is used. The collar so constructed is laundered with no more difficulty than a collar having an ordinary band.

5 In the modified form shown in Fig. 2 of the drawing instead of employing a plurality of short strips and arranging them vertically, at more or less frequent intervals, between the plies of the neck band of the 10 collar, I employ a plurality of longitudinally arranged strips or plies of similar material lettered respectively 11, 12 and 13 which may be of any convenient length and width, and quilt or sew the same together in 15 the manner illustrated in the drawing, thereby obtaining the same result.

Experience has demonstrated that the organization above described is a practical and efficient one for accomplishing the ends 20 sought by this invention. The construction

may, however, be varied in detail by those skilled in such matters, without departing from the invention.

Having thus described my invention, I claim as new and desire to secure by Letters 25 Patent:

A soft fold-collar having a top, and a neck band composed of a plurality of plies, and independent spaced strips of fabric arranged vertically at frequent intervals, permanently secured between the plies of the band by reinforcing stitching inserted through said plies and strips. 30

This specification signed and witnessed this 20th day of November, 1917.

SÁNDOR WEISZ.
